US00D894772S

(12) **United States Design Patent** (10) Patent No.: **US D894,772 S**
(45) Date of Patent: ** Sep. 1, 2020

(54) **FIRE ALARM**

(71) Applicant: **HOCHIKI CORPORATION**, Tokyo
(JP)

(72) Inventors: **Hayato Tsurumi**, Tokyo (JP); **Manabu Enomoto**, Tokyo (JP)

(73) Assignee: **Hochiki Corporation**, Tokyo (JP)

(**) Term: **15 Years**

(21) Appl. No.: **35/504,148**

(22) Filed: **Jun. 14, 2017**

(80) **Hague Agreement Data**

Int. Filing Date: **Jun. 14, 2017**

Int. Reg. No.: **DM/096579**

Int. Reg. Date: **Jun. 14, 2017**

Int. Reg. Pub. Date: **Dec. 15, 2017**

(51) **LOC (12) Cl.** 10-05

(52) **U.S. Cl.**

USPC **D10/106.5**

(58) **Field of Classification Search**

USPC D10/106.1, 0.2, 0.5, 109.2, 116.1, 120
